UNITED STATES PATENT OFFICE.

JOHN C. DOANE, OF EAST HARTFORD, CONNECTICUT, ASSIGNEE TO UNDERWOOD TYPEWRITER COMPANY, OF NEW YORK, N. Y., A CORPORATION OF DELAWARE.

TYPEWRITING-MACHINE.

1,384,122.

Specification of Letters Patent. Patented July 12, 1921.

Application filed December 5, 1918. Serial No. 265,225.

To all whom it may concern:

Be it known that I, JOHN C. DOANE, a citizen of the United States, residing in East Hartford, in the county of Hartford and 5 State of Connecticut, have invented certain new and useful Improvements in Typewriting-Machines, of which the following is a specification.

This invention relates to typewriting machines, and is herein disclosed as applied to the platen-scale of an Underwood typewriting machine. In such machines, the scale has usually hitherto been made independent of the case-shift mechanism, with the result 15 that as the platen rises in the case-shift operation, it rises away from the scale. According to the present invention, the scale may rise with the platen at the case-shift operation, with the result that characters written 20 in the upper case will lie adjacent the scale while in the upper case, just as characters written in the lower case are adjacent the scale in the ordinary machine.

To obtain this result, there is provided a 25 mechanism for supporting the platen-scale, such that the motion of the shift frame about its axis may be converted into a substantially vertical motion for the scale adjacent the platen. Each end of the scale is 30 also supported independently, and each link-support is connected to the shift frame.

Other features and advantages will hereinafter appear.

In the accompanying drawings—

35 Figure 1 is a perspective view of an Underwood typewriting machine, showing the present invention as applied thereto, many parts being omitted or broken away.

Fig. 2 is a sectional side view, largely diagrammatic, of the machine in position for writing lower-case characters.

Fig. 3 is a fragmentary view showing many of the parts seen in Fig. 2 from the end, with the machine writing characters in 45 upper case.

In the Underwood typewriting machine, character keys 1, when depressed, carry down their key-levers 2, thereby swinging sub-levers 3 to carry type-bars 4 upwardly 50 and rearwardly, so that lower-case types 5 and upper-case types 6 on the type-bars will print against the front side of a platen 7, which is rotatably mounted in the platen frame 8. The platen frame forms part of a 55 carriage 9, said carriage having pivoted

thereon a rack 10 meshing with a pinion 11, connected to an escapement wheel 12, so that the carriage may be fed along thereby to the left at each actuation of any key 1, there being provided for this purpose the usual 60 dogs 13 and the spring barrel (not shown). In order to actuate the dogs 13, there is a universal bar 14 fast to a segment 15, which is adapted to be struck by heels 16 on the type-bars 4 as they approach the platen, and 65 thereby vibrate the dogs rearwardly.

Writing is normally done with the lower-case type 5. When it is desired to write in upper case, a shift-key 17 on the front end of a key-lever 18 is depressed, so that an up-standing arm 19, at the rear end of its lever, will rock a bell-crank 20, forming part of a frame which also includes the carriage-shift-rail 21. When a key is thus depressed, to lift the rail 21, the platen frame 8 is 75 shifted upwardly, because it runs by a wheel 22 on the rail 21, and is guided in vertical direction by the usual arms 23 journaled at 24 at the rear of the carriage 9.

In order to enable the typist to quickly 80 and accurately identify the position of the characters written on a work-sheet passed around the platen 7, there is provided a scale-plate 25, adjacent the platen and graduated at letter-space intervals to correspond 85 to the spacing of the front scale 26. The scale-plate 25 is relatively short and comprises two wings extending on either side of a slot 27 at the type-guide 28,—the slot being deep enough to allow the lower-case 90 type 5 to be clear of the scale-plate 25 when writing in upper-case position.

According to the present invention, the scale 25 is adapted to rise with the platen when the latter is raised by the rail 21. To 95 thus raise the scale-plate 25, each bell-crank 20 is provided with a plate 29, on which is fast a forwardly-extending arm 30; each arm connected to raise a frame or support 31 for its end of the scale-plate 25. Each 100 support 31 is pivoted on a bracket 32, which extends toward the front of the machine, there being one bracket at each side of the machine, and each bracket 32 is formed of a hollow square of sheet-metal, so that it 105 can lie around the mounting 33 of the usual ribbon-spool-shaft. To enable the brackets 32 to be readily attached to the machine, each is provided with an opening 34, through 110 which may pass the usual screw 35, which

holds the bracket 36 of the ribbon-spool to the frame of the machine. By having the brackets 32 made in the form of hollow squares, it is possible to have two widely separated pivots 38 near the front of the machine, one pivot at the end of each extremity of each bracket for the support or frame 31, thus giving great rigidity to the support of each end of the scale-plate 25, with the result that the scale-plate itself may be exceedingly light. The pivots 38 pass through turned-up ears 39 on the brackets and turned-up ears 40 on the frames 31. To enable the frames 31 to be supported in this way, each is formed as a hollow square having sides 41, said square having one edge 42 lying near the plane of the segment 43. To attach the scale-plate 25 to the hollow squares 41, each hollow square 41 has an ear 44 turned up therefrom, and extending over the surface of the top of the segment 43, and then bent parallel to the scale-plate 25. To each ear is attached, by a pair of screws 45, a bracket 46 having a turned-over end 47 adapted to embrace and be pivoted to turned-up ears 48 on the lower edge of the scale-plate 25. Since there is a pair of ears 48 at each end of the scale-plate 25 and a bracket 46 pivoted to said ears, the two ends of the scale-plate 25 are strongly and independently supported from the ends of the shift frame, thus avoiding all tendency to twist the scale-plate 25. At the same time, there is nothing in front of the type-guide to interfere either with the type-bars or with the view of the writing on the work-sheet.

The connections for lifting the frames 31 include short, nearly vertical, links 49, pivoted to the arms 30 and also pivoted to forwardly-extending arms 50, which, in turn, are pivoted at 51 to downward arms or projections 52 of the brackets 32. Thus, each pivoted arm 50 forms a member which rocks nearly vertically whenever the case-shift-key 17 is depressed, with the result that it can carry up, practically vertically, a link 53 pivoted to it, and also pivoted to a downwardly-turned ear 54 of its frame 31.

In order to secure the desirable uniformity of operation in the scale-raising mechanism, there is provided a link 49, an arm 50, an arm 52, and a link 53 for each frame 31, with the result that the platen-scale 25 is raised symmetrically and uniformly at both ends whenever the shift frame, which includes the rail 21, is raised.

In order to hold the platen-scale 25 against the platen, there are provided downwardly-extending springy fingers 55 stamped out of the scale-plate, one finger below each pair of ears 48, said fingers adapted to lie against the face of the segment 43, and thereby swing the upper end of the scale-plate 25 against the platen. In upper-case

position, the scale-plate 25 may be held upright by the humps 60 on the fingers 55 which are sprung against the interiors of the brackets 46, because of the pressure of the fingers 55 on the segment 43. To form a rest for the frame 31 in its lower-case position, each ear 54 has a lug 56 extending forwardly therefrom; each lug adapted to rest on the rear edge 57 of the bracket 32. To steady the frames 31 in their upper positions, each ear 54 is provided with a second lug 58, which is adapted to strike the edge 57 when the scale-plate 25 is raised.

A frame 31 and its arm 50 connected by a link 53 form a quasi-parallel motion device, causing the scale-plate 25 to closely follow the platen which is guided by the quasi-parallel motion device formed by the arms or links 23 and bell-cranks 20.

It will be observed that the device herein illustrated is adapted to be attached to any ordinary Underwood typewriting machine. The principal screws for attaching the hollow square brackets 32 may be the usual screws, or somewhat longer screws, adapted to fit the usual holes 34. In order to give additional rigidity to the device, the rear parts of the brackets 39, where nearest to the type-guide 28, may be provided with ears 61 adapted to fit against the bottom of the usual extensions 62 of the ribbon-spool-brackets 36, and to be screwed thereto.

Variations may be resorted to within the scope of the invention, and portions of the improvements may be used without others.

Having thus described my invention, I claim:

1. The combination with a typewriting machine having a segment and a pair of ribbon-supporting devices one at each side of the segment, of a platen, a shift-frame for the platen, a scale in front of said platen, a support for each end of said scale pivoted to the corresponding ribbon-supporting device, and a linkage between said shift-frame and each of the scale-supports for shifting said scale with said platen.

2. The combination with a typewriting machine having a segment and a pair of ribbon-supporting devices one at each side of the segment, of a platen, a shift-frame for the platen, a scale in front of said platen, a support for each end of said scale pivoted to the corresponding ribbon-supporting device, and a parallel-motion linkage between said shift-frame and each of the scale-supports for rocking said supports to shift said scale with said platen.

3. In a typewriting machine having a segment and a platen shift-frame, the combination with a platen, of a scale therefor, a swinging support in front of the segment on which the scale is pivoted, and a guiding device for the scale co-operating with the segment to hold the scale upright.

4. In a typewriting machine having a segment and a platen shift-frame, the combination with a platen, of a scale therefor, a swinging support in front of the segment 5 on which the scale is pivoted, and springs extending from the scale and bearing against the segment to hold the scale upright.
5. In a typewriting machine having a segment and a platen shift-frame, the combination with a platen, of a scale therefor, a swinging support in front of the segment 10 on which the scale is pivoted, springs extending from the scale and bearing against the segment to hold the scale upright, and means forming part of the swinging support to hold the springs against the segment.
6. In a typewriting machine having a type segment, a platen, and a shift-frame, the combination with a platen scale, of a frame on which the scale is pivoted, pivots for said frame in front of the platen and substantially within the limits of the vertical shifting of the platen, and means for holding the scale against the platen.
7. In a typewriting machine having a type segment and a platen shift-frame, the combination with a platen, of a scale therefor, a pivot bar in front of the segment to support the scale, and a link connecting the scale to the shift-frame.
8. In a typewriting machine having a segment and a platen shift-frame, the combination with a platen and a scale therefor, of a support independent of the platen for each end of the scale, pivots in front of the segment for said supports, and a link from each support to the shift-frame.
9. In a typewriting machine having a segment and a platen shift-frame, the combination with a platen and a scale therefor, of a support independent of the platen for each end of the scale, pivots in front of the segment for said supports, a link from each support to the shift-frame, pivots by which the scale is carried on its support, and means for holding the scale upright on its pivots.
10. The combination with a typewriting machine having a segment and a pair of ribbon-supporting devices one at each side of the segment, of a platen, a shift-frame for the platen, a scale in front of said platen, a support for each end of said scale comprising a frame pivoted at one edge to a ribbon-supporting device and having an arm fixed to a parallel edge and pivoted to said scale, depending vertical members on an adjacent edge of said scale-support, a link connecting said vertical members, and means connecting said shift-frame and link for rocking the scale-support to shift the scale with the platen.
11. The combination with a typewriting machine having a segment and a ribbon-
supporting device, of a platen, a shift-frame for the platen, a scale therefor, a frame embracing said supporting device, a pivot on each end of the scale-supporting device to guide it, and a link connecting said scale support to the shift-frame.
12. The combination with a typewriting machine having a segment and a pair of ribbon-supporting devices, one at each side of the segment, of a platen, a shift-frame for the platen, a scale, a scale support for each end of the scale, each support comprising a frame embracing a ribbon-supporting device, a pivot at each end of each scale support to guide it, and a link connecting each scale support to the frame.
13. The combination with a platen and a shift-frame, of a scale for the platen, a quasi-parallel motion mounting for each end of the scale, and a link connecting each end of the shift-frame to its mounting to cause the ends of the scale to move together.
14. In a typewriting machine having a segment and a platen, the combination with a platen-shift-frame, of a scale-plate for the platen, a swinging support at each side of the segment and in front thereof on which the scale-plate is pivoted, a guide for the scale-plate coöoperating with the segment, and a link for each support for causing the two ends of the scale-plate to move together.
15. In a typewriting machine having a segment and a platen, the combination with a platen shift-frame, of a platen scale, a pair of pivoted bars in front of the segment to support the scale at each end thereof, and a link at each end of the shift-frame connecting the scale to the shift-frame.
16. The combination with a typewriting machine having a segment and a ribbon-supporting device, of a platen, a scale therefor, a shift-frame for the platen, a scale support comprising a frame embracing said supporting device, a pivot at each end of the scale-supporting device to guide it, a link connecting said scale support to the shift-frame, pivots on the scale support for supporting the scale, and spring guides for holding the scale vertical.
17. In a typewriting machine having a segment and a platen shift-frame, the combination with a platen and a scale therefor, of a support independent of the platen for each end of the scale, pivots in front of the segment for said supports, a link from each support to the shift-frame, and lugs for steadyng the scale support at each end of the throw of the scale when shifted.
18. The combination with a typewriting machine having a segment and a ribbon-supporting device, of a platen, a scale therefor, a shift-frame for the platen, a scale support comprising a frame embracing said supporting device, a pivot on each end of the scale-supporting device to guide it, and a link connecting said scale support to the shift-frame.

support comprising a frame embracing said supporting device, a pivot at each end of the scale-supporting device to guide it, a link connecting said scale support to the shift-frame, and lugs for steadyng the scale support at each end of the throw of the scale when shifted.

19. In a typewriting machine, the combination with a platen and a shift-frame therefor, of arms pivoted near the front of the machine and at each end thereof, vertical links connecting the arms at each end, a scale supported by said links, and a link connected to the shift-frame to shift said arms.

20. In a typewriting machine, the combination with a platen and a shift-frame therefor, of a scale for the platen, an independent support for each end of the scale pivoted near the front of the machine, and a link at each end of the shift-frame to cause each support to swing with the shifting of the shift-frame, and lugs for steadyng the scale support at each end of the throw of the scale when shifted.

21. In a typewriting machine, the combination with a platen and a shift-frame therefor, of a scale for the platen, an independent support for each end of the scale pivoted near the front of the machine, a link at each end of the shift-frame to cause each support to swing with the shifting of the shift-frame, and springs for holding the scale against the platen as it shifts.

JOHN C. DOANE.
